NOTEBOOK

John F. Misak, Jr., Chicago, Ill.

Application May 1, 1948, Serial No. 24,526

3 Claims. (Cl. 281—30)

1

The present invention relates to improvements in notebooks, and particularly pocket notebooks adapted to be carried about for entering personal memoranda.

It is a matter of considerable convenience to provide notebooks of the foregoing character with some form of pencil holder so that a pencil will be available when needed. Pencil holders for various types of notebooks and writing pads have been provided heretofore, but in so far as I am aware, merely in the form of a simple tubular sleeve or loop secured to the exterior of the book or pad and adapted simply to have the pencil inserted longitudinally therethrough. Such prior pencil holders have been subject to objection for various reasons. Thus, they are unsightly and awkward; they do not adequately protect the writing point of the pencil; they do not fit snugly about pencils of different diametrical sizes, and when made of composition, cloth or leather may enlarge and as a result fail to hold the pencils securely.

One of the objects of the present invention is to provide a notebook with a new and improved pencil holder which overcomes the objections enumerated above to prior holders, and which, more particularly, will receive and hold securely pencils of different thicknesses, protect the writing point thereof against breakage, and remain efficient and reliable over a period of long continued use.

Another object is to provide a pencil holder of the foregoing character which is suitably attached in position at some convenient location entirely between the covers of the notebook so as to be out of sight when the book is closed and thereby to avoid awkwardness and impairment of appearance.

Further objects and advantages will become apparent as the description proceeds.

In the accompanying drawings, Figure 1 is a perspective view of a notebook in partially open position and provided with a pencil holder embodying the features of the present invention.

Fig. 2 is a fragmentary plan view of the pencil holder.

Fig. 3 is a fragmentary transverse sectional view taken along line 3—3 of Fig. 2.

Fig. 4 is a fragmentary transverse sectional view taken along line 4—4 of Fig. 2.

Referring more particularly to the drawings, the notebook constituting the exemplary embodiment of the invention comprises an outer cover having a bottom member 5 and a top member 6 joined together at one end by a connecting back

wall 7. While one particular type of cover has been shown, it is to be understood that the invention is broadly applicable to notebooks of various types with various arrangements of covers.

In the specific embodiment herein disclosed, each of the cover members 5 and 6 comprises an outer layer 8 of a suitable material, such as cloth, leather or imitation leather, with longitudinal and outer end marginal portions folded inwardly as indicated at 9. Attached by means of a suitable adhesive to the inner surface of the layer 8 is a liner 10 of suitable material.

Suitably confined within the cover are the conventional leaves 11 of the notebook. The leaves may be of any suitable character and attached in any desired manner. In the present instance, the leaves 11 are of the loose-leaf type, and are attached at one end to the cover by means of suitable binding rings 12. Also, the leaves 11 are made appreciably shorter than the cover members 5 and 6, and are so located endwise as to provide at one end between the cover members a conveniently located space to receive a pencil holder 13 according to the present invention. Preferably, the rings 12 are anchored to the back wall 7 whereby to provide such a space between the free outer end portions of the cover members 5 and 6.

30 The pencil holder 13 may be attached to the inner surface of either one of the cover members 5 and 6, and, in the specific arrangement shown, is attached to the member 5 in position beyond the free outer ends of the leaves 11.

35 In the preferred form, the pencil holder 13 comprises a stiffening or reinforcing member 14 in the shape of a flat rectangular base strip made of a suitable material, such as wood or stiff fibre composition. This strip extends crosswise of the member 5 and is glued or otherwise suitably secured thereto.

40 Disposed along and against the opposite longitudinal marginal side portions of the exposed face of the strip are two opposed parallel elongated side flaps 15. The remote outer longitudinal marginal edge portions of the flaps 15 are glued or otherwise suitably secured to the strip 14 in laminar relation therewith, and the adjacent longitudinal marginal edge portions thereof are left free, and pressed upwardly away from the strip and shaped to receive a short pencil 16 therebetween. Preferably, the flaps 15 are made of a suitable material, such as leather, which may be pressed out of a flat condition into a sustaining 45 shape conforming generally to the longitudinal

contour of the pointed end of the pencil 16, and which when so shaped will be slightly yieldable to exert a holding action on the pencil.

The holding flaps 15 may conveniently be formed out of an integral top strip 17 overlying and coextensive in shape with the base strip 14. To define the lifted portions of the flaps 15, the top strip 17 is cut with parallel transverse slits 18 respectively adjacent opposite ends thereof and with a longitudinal medial slit 19 extending fully therebetween. The marginal end portions of the top strip 17, located outwardly of the slits 18, are secured to the base strip 14 in the same manner as the longitudinal marginal side portions. As a consequence, the material at opposite sides of the slit 19 between the slits 18 may be lifted and shaped to form the inclined flaps 15, which in cooperation with the underlying base strip 14 define a socket 20 open at one end to receive the pencil 16 and substantially closed and tapered at the other end to embrace the pencil tip.

To facilitate ready insertion and removal of the leaves or pages 11 as the need arises, the binding rings 12 may be provided in a pair spaced apart slightly less than the width of the pages to engage in notches 21 cut in the side edges of the latter adjacent the inner end edges. The two spaced rings 12 may be formed of plastic sheet material rigidly fixed to a backing member 22 attached to the wall 7. The notches 21 define narrow hinge tongues 23 which, upon laterally flexing and then releasing the leaves 11, may be inserted into the rings 12.

It will be evident that I have provided a simple, inexpensive and convenient pencil holder adapted to be constructed as an integral part of a pocket notebook or the like. In the preferred form shown, the base strip 14 serves to stiffen against lateral flexure the outer end portion of the cover member 5 to which it is attached. This is especially desirable in instances where the cover member 5 is of flexible instead of rigid construction. By reason of this inflexible base construction, and the enclosure of the tip of the pencil 16 by the closely conforming flaps 15, the writing point is protected against breakage. Due to their slightly resilient characteristics, the flaps 15 not only afford an efficient and reliable means for gripping the pencil 16 securely even after long continued use, but are adaptable to receive and conform to pencils of different thicknesses. In general, the pencil holder is normally concealed when the book is closed so that it does not constitute an awkward exterior appendage, and the pencil when inserted therein is not susceptible of inadvertent removal and loss. The pencil nevertheless may be easily and quickly inserted and removed, and is always available when needed.

Mounting the pencil holder 13 to extend crosswise of the bottom cover member 5 is of particular advantage, especially in notebooks which open from one end, as shown in Fig. 1. Notebooks of this type are often carried in hip pockets and therefore subject to flexure when the user sits down. With the pencil disposed crosswise, rather than longitudinally of the line of flexure, it is not subjected to any breaking force.

I claim as my invention:

1. A pencil holder adapted to be mounted on a backing member comprising, in combination, an elongated narrow base strip of stiff material adapted to be securely attached at its back side to a backing member, an elongated top

strip of resilient material disposed in overlying relation to said base strip and substantially coextensive therewith, said top strip being attached along its edge margins to said base strip and having two transverse slits therein disposed slightly inwardly from opposite ends thereof, the mid-portions of said slits being interconnected by a longitudinal medial slit so as to define two opposed, elongated pencil gripping flaps on said top strip, each flap extending between said transverse slits and running the major portion of the length of said base and top strips, said flaps being lifted at their free edges from the plane of said top strip to form an elastic pencil holding socket, and the lifting of said flaps at one end of said strips being at a substantial angle to said base strip to provide an open end to said socket for insertion of a pencil, the opposite ends of said flaps being lifted at a smaller angle to said base strip to provide a tapered portion in the opposite end of said socket to protectively and resiliently grip the pointed end of a pencil.

2. A pencil holder adapted to be mounted on a backing member comprising, in combination, an elongated narrow base strip of stiff material adapted to be securely attached at its back side to a backing member, an elongated top strip of resilient material disposed in overlying relation to said base strip and substantially coextensive therewith, said top strip being attached along its edge margins to said base strip, a medial slit extending longitudinally along the mid-portion of said top strip so as to define two opposed, elongated pencil gripping flaps on said top strip, each flap running the major portion of the length of said base and top strips, said flaps being lifted at their free edges from the plane of said top strip to form an elastic pencil holding socket, and the lifting of said flaps at one end of said strips being at a substantial angle to said base strip to provide an open end to said socket for insertion of a pencil, the lifting of said flaps at the opposite end of said strips being at a smaller angle to said base strip to provide a tapered end portion on said socket opposite said open end to protectively and resiliently grip the pointed end of a pencil.

3. A paper and pencil holder device of the character described comprising, in combination, retaining means adapted to be secured to one marginal edge of a stack of notebook paper to hold the sheets of paper in assembled relationship with said means, two rectangular cover members each interconnected along one marginal edge to said retaining means, said cover members being adapted to extend in overlying relationship to opposite sides of a stack of paper to be attached to said retaining means, said covers each being longer than the stack of papers so as to present one marginal edge of substantial width disposed opposite said retaining means and adapted to extend beyond the end of the paper stack, a pencil holder mounted on said marginal edge of a first one of said covers so as to be disposed in protected relation to said marginal edge of the second one of said covers, said holder comprising an elongated narrow base strip of stiff material having a width substantially equal to the width of said marginal edge of said first cover and securely attached at its back side to said last mentioned marginal edge in parallel relation thereto, an elongated top strip of resilient material disposed in overlying relation to said base strip and substantially coextensive therewith, said top strip being attached along

its edge margins to said base strip and having two transverse slits therein disposed somewhat inwardly of opposite ends thereof, the mid-portions of said slits being interconnected by a longitudinal medial slit so as to define two opposed, elongated pencil gripping flaps on said top strip, each flap extending between said transverse slits and running the major portion of the length of said base and top strips, said flaps being lifted at their free edges from the plane of said top strip to form an elastic pencil holding socket, and the lifting of said flaps at one end of said strips being at a substantial angle to said base strip to provide an open end to said socket for insertion of a pencil, the lifting of the opposite ends of said flaps being at a smaller angle to said base strip to provide a tapered end portion on said socket to protectively grip the pointed end of a pencil.
